UNITED STATES PATENT OFFICE.

DOUGLAS VAUGHAN JOHNSTONE AND JOHN WILLIAM FEARN, OF BIRMINGHAM,
ENGLAND.

AIR PISTOL, AIR RIFLE, AND SIMILAR WEAPON.

Application filed March 27, 1924. Serial No. 702,253.

To all whom it may concern:

Be it known that DOUGLAS VAUGHAN JOHNSTONE and JOHN WILLIAM FEARN, subjects of the King of Great Britain, residing at 81-91 Weaman Street, Birmingham, England, have invented certain new and useful Improvements in Air Pistols, Air Rifles, and Similar Weapons, of which the following is a specification.

10 This invention has reference to air-pistols, air-rifles, and similar pneumatic weapons of the type in which a hinged barrel is adapted to be used as a lever for "cocking" the weapon, i. e., for displacing 15 the spring-loaded piston within the air-chamber into engagement with the sear of the lock.

According to the said invention, and with the object of providing a compact, efficient 20 and accurately-shooting weapon capable of being manufactured at a relatively low cost, the barrel is superimposed on, and normally secured in parallel relationship to, the air chamber, and is suitably jointed to the said 25 chamber (or to the body of the weapon) and linked to a cocking slide or equivalent device that is displaceable along a slot in the chamber walls for imparting the cocking movement to the air-displacing piston; 30 the arrangement of the barrel, link and cocking-slide mechanism being such that, during the angular movement of the barrel in the cocking direction, the piston will be displaced into engagement with the sear of 35 the lock, whilst during the reverse movement of the said barrel, the link and slide make an idle movement relatively to and independent of the said piston.

This construction enables an effective 40 cocking leverage to be obtained with a relatively short barrel, and thus renders the invention particularly applicable to air-pistols.

The cocking-barrel may be jointed to the 45 air-chamber or body at either its muzzle or breech end, and in the accompanying drawings,

50 Figures 1 to 11 show, by way of example, an air-pistol constructed in accordance with the invention in which the barrel element is jointed at the muzzle end.

Figure 1 of the said drawings is an elevation of such a pistol with the cocking barrel locked in its normal or firing position.

Figure 2 is a similar view showing the 55 barrel at the end of its cocking stroke.

Figure 3 is a sectional elevation, on a larger scale, of the complete pistol, and shows the arrangement of the cocking mechanism, the connection between the cocking 60 slide and the air-displacing piston, and the air-passage connections between the air-chamber and the breech end of the barrel. It also shows the lock and safety mechanism.

Figure 4 is an elevation showing the locking device or catch used for securing the 65 barrel in its normal position, and

Figure 5 is a section thereof on the dotted line 5—5.

Figure 6 is a section on the line 6—6, 70 Figure 3, showing the connection between the cocking slide and the piston.

Figure 7 is an elevation of the muzzle end of the pistol, showing the construction of 75 the barrel joint.

Figure 8 is an elevation showing the safety bolt which may be associated with the lock mechanism of the pistol.

Figures 9 and 10 are horizontal sectional views further illustrating the safety bolt 80 arrangement, Figure 9 showing the bolt in its normal position, whilst Figure 10 shows the same in a position to which it must be displaced before it can be turned from the "on" to the "off" position, or vice versa.

Figure 11 is a detail view showing the lock mechanism and the safety bolt; the latter being illustrated in its "off" position, whereas in the general view Figure 3 the said bolt is shown in the "on" position 90 in which it locks the trigger but leaves the sear free to play during the cocking of the weapon.

Figure 12 is a sectional elevation of a modified or alternative construction of air 95 pistol in which the cocking-barrel is hinged at the breech end of the weapon.

The same letters of reference indicate corresponding parts in the said Figures 100 to 11.

In the pistol illustrated, the air chamber *a*, which constitutes the body of the weapon, is mounted on a handle or grip *a'* and is fitted with a suitable lock mechanism conveniently disposed in front of the said handle, whilst internally the said chamber is provided with a spring-loaded piston *b* which, during its "firing" stroke displaces

air from the rear portion a^2 of the chamber through passages c, c' , communicating with the breech end of the barrel d . The piston is provided, at or near its opposite ends, 5 with collars or shoulders b', b^2 , of which the former b' , serves as an engagement for the sear e of the lock when the piston is cocked, whilst the front collar b^2 provides an engagement for a cocking slide f (see Figures 3 and 6) that is located inside the chamber and has a lug f' extending through a slot g cut longitudinally in the front upper part of the said chamber. The length and disposition of this slot g are such that 10 whilst providing for an adequate cocking and return stroke of the slide f , it is nevertheless always isolated from the rear portion a^2 of the chamber a by the piston-washer b^3 , so that air cannot escape by way 15 of the said slot during the firing stroke of the piston.

The barrel d is superimposed on and is normally held in parallel relationship to the air-chamber as shown in Figures 1 and 3, 20 whilst to provide for its use as a cocking lever, the muzzle end is carried by a swinging bracket h jointed at h' to the front of the air-chamber, whilst its breech end engages an open-topped seating i' of a second 25 but fixed bracket i^2 which is elevated from the rear end of the said chamber and where-through the air passages c, c' are formed so that air displaced from the chamber during 30 the rearward movement of the piston is conveyed to the back of, and effects the discharge of, a pellet or other missile previously inserted in the barrel-breech. A 35 spring catch, such as j is fitted to the bracket i^2 , and serves to engage the breech end of the barrel for firmly securing the latter in 40 its normal position but in such a manner that the said breech end can be readily lifted out of its seating i' when it is required to load a pellet into the breech or make use of 45 the barrel as a cocking lever.

To maintain an air-tight joint between the barrel breech and the air-passage c' of the bracket i^2 , a leather or other compressible washer is located in the said passage c' 50 and is so disposed that the breech-face of the barrel, when closed, makes close contact with the outer face of the said washer as shown in Figure 3.

A back-sight h^2 may be mounted on the 55 rear face of the fixed bracket i^2 and the foresight h' is preferably carried on top of the swinging bracket h' , whilst to ensure that the barrel shall be maintained in accurate sighting alignment between its two supports, 60 the bracket h' is of a substantial character and is arranged to fit within, and be held against lateral displacement by, an open-fronted slot h^2 in the air-chamber; a substantial joint-pin also being used to form the 65 bracket-pivot. This slot h^2 is located in the

central plane of the air-chamber and in exact alignment with the similarly-disposed rear seating i' that receives and positions the breech end of the barrel.

For cocking purposes, the barrel is connected to the cocking slide f by a link k , hinged at its forward end to the barrel and at its rearward extremity to the slide-lug f' ; the arrangement and disposition of this linkage in relation to the barrel joint being such 70 that when the said barrel is levered or swung upwardly on the said joint, the slide f is constrained to travel forwardly in the slot g . Thus if the barrel is so levered when the piston is at the rear end of the air-chamber 75 (i. e. in its fired position) the cocking slide will immediately engage behind the front collar b^2 of the said piston and, in traversing the slot g as the barrel movement continues, will displace the piston forwardly until the 80 rear shoulder b' thereof comes in front of and is engaged by the sear of the lock mechanism, whereby the said piston is retained in the cocked position, with its actuating 85 spring in compression. The weapon may 90 then be loaded by placing a pellet in the elevated breech end of the barrel, after which the said barrel is restored to its normal position by depressing the breech end into engagement with the rear-bracket seating i' , the link meanwhile displacing the 95 cocking slide idly and rearwardly in the chamber to the position where it will be re-engaged by the front collar b^2 of the piston when the arm is again discharged. 100

The lock comprises a sear e whose nose e' is adapted to engage the collar b' of the piston and whose tail e^2 extends a distance rearwardly of the sear axis-pin whilst the trigger e^3 is pivoted on an axis-pin disposed below and to the rear of the sear-axis, and has a tail e^4 that bears on the underside of the sear-tail, the arrangement being such that on the trigger being pulled, its tail 105 levers upwards the tail of the sear and depresses the nose e^5 which effects discharge 110 of the weapon if the trigger is so pulled when the sear is in engagement with the piston-collar b' .

This lock is associated with a safety device which, when applied, prevents movement of the trigger but leaves the sear free to play on its axis pin. This enables the safety to be put "on" before the piston is 115 cocked, since the freedom of the sear will allow the nose-end to be depressed as the collar b' rides over the inclined surface e^5 of the said nose during the cocking stroke of the piston, whilst after the said collar has passed beyond the said nose, the sear-spring will lift the front of the sear and engage the nose at the back of the collar as 120 shown in Figure 3.

The safety device shown in the drawings 125 comprises a bolt o rotatably mounted trans-

versely in the body of the weapon, immediately behind the tail of the trigger. The bolt has a recess o^1 in which the trigger-tail plays; at the back of the recess are two flat surfaces o^2 , o^3 set at an angle to one another as shown in Figures 3 and 11. The bolt is operated by an external finger-piece and when in the "off" position, the flats o^2 , o^3 behind the bolt-recess o^1 are disposed so that they do not impede movement of the trigger (see Figure 11) whereas by turning the bolt into the "on" position, Figure 3, the flat o^2 is brought over the extremity of the trigger-tail and so locks the latter that it cannot be displaced when pulled.

To enable the bolt to be positively locked in both its "on" and "off" positions, the said bolt is so mounted that it can slide 20 transversely to the body and is influenced by a spring tending to press the same outwards, whilst its outer end is formed with two edge recesses o^6 , o^7 , disposed at a suitable angular distance apart and adapted to 25 engage a retaining-piece o^8 that is fixed outside the body. The recess o^6 engages (by the outward thrust of the spring o^5) the retaining piece when the safety is "off" and the other recess o^7 similarly engages 30 when the safety is "on," whilst to permit of the bolt being turned from one position to the other, it is merely necessary to displace the latter inwards by finger pressure a sufficient distance to clear the engaging 35 recess from the retaining piece, when the bolt can be turned in the desired direction, and to the necessary extent to bring the other recess into register with the piece o^8 ; the spring automatically re-establishing the 40 lock when finger pressure is relieved on completion of the rotational movement of the bolt.

A modified or alternative construction of air-pistol in which the cocking-barrel is 45 hinged at the breech end is shown in sectional elevation in Figure 12.

Here the breech end of the barrel d is carried in a stirrup pivoting on the rear bracket i^2 and is provided, at or near its muzzle end, with a depending piece h which, on the said barrel being closed into its normal position, engages in an open-fronted slot h^2 in the forward end of the chamber a and is there retained by a spring catch or fastening j ; the piece h being made an accurate fit in the slot h^2 to prevent lateral play of the barrel and preserve same in accurate sighting alignment with the breech end.

With this breech-jointed barrel, it is 60 advantageous to provide for the cocking of the piston to be effected during the upward stroke of the said barrel, which necessitates the piston being displaced from front to rear of the air-chamber and the provision 65 of some means for conveying air displaced

from the front of the said chamber to the passages connecting the chamber with the barrel-breech. To realize this, the slot g wherein the cocking slide f travels is formed in the rear part of the air-chamber 70 and the rear collar b^1 of the piston serves as the engagement for the slide during the rearward stroke of the latter, whilst the front collar b^2 constitutes the engagement for the lock-sear. Further, to provide for 75 the conveyance of displaced air from the front part of the chamber a to the breech, a tube m is fixed axially in the said chamber and formed with ports m' at its front end, whilst its rear end is in connection with the 80 passages c , c' leading to the breech. Or a passage or passages for leading or conveying air from front of the chamber to the breech may be formed on the outside of the chamber or body as an alternative to using 85 an axial tube m .

A pistol of this construction may be 90 loaded by inserting a pellet directly into the barrel-breech after the cocking stroke of the said barrel has been completed. Or loading when the barrel is closed may be provided for by fitting in the rear of the bracket, and in alignment with the barrel-bore, a loading hole normally closed by a 95 screw plug n which can be removed to enable a pellet or missile to be inserted into the barrel by way of the said hole. This plug n may be furnished, at its inner end, with a peg or stem whereby a pellet inserted 100 into the entrance rear end of the loading hole is pushed home into the breech end of the barrel during the screwing of the said plug into its place.

As an alternative provision for jointing 105 the barrel and loading, the breech end of the said barrel may be furnished with trunnions mounted in bearings in a pair of separated lugs or brackets standing above the breech-end of the air-chamber; and one of these trunnions may be fitted with a 110 rotary loading plug disposed transversely to the barrel axis between the barrel-breech and the air passage leading from the air-chamber; the pellet-chamber of the said plug being so disposed that, by the actuation 115 of a suitably-arranged lever or finger-piece, it can be set to register with a loading aperture in the top of the barrel, or disposed in alignment with the bore of the barrel and the air passage. This construction permits of the weapon being loaded 120 when the barrel is closed and secured in its normal position above the air-chamber

The application of our invention to air-rifles and other pneumatic weapons differs 125 in no essential respect from its application to air-pistols as herein described.

Having described our invention what we claim and desire to secure by Letters Patent is:—

1. An air-pistol or other pneumatic weapon wherein the hinged barrel, which also serves as the cocking lever, is superimposed upon, and normally secured in parallel relationship to, the air-chamber, and is adapted to displace the spring plunger in the cocking direction when levered upwardly from the said chamber. 35
2. An air-pistol or other pneumatic weapon wherein the barrel is superimposed upon and hinged to the air chamber, and a cocking-link is so arranged between the said barrel and the spring plunger as to provide for displacement of the said plunger in the 40 cocking direction when the barrel, which normally is fastened in parallel relationship to the air chamber, is levered upwardly. 45
3. A pneumatic weapon according to claim 2 in which the air chamber is slotted upon its top side and fitted with a cocking slide to which the cocking-link is pivoted, and which positively engages the spring plunger during cocking movement of the barrel. 50
4. A pneumatic weapon wherein a hinged barrel which also serves as a cocking lever, is jointed to the air-chamber or body of the weapon, and its breech end is adapted normally to engage an open-topped seating in the rear of the said chamber or body; the 55 back of the said seating being in communication with an air-passage for making connection between the air-chamber and the bore of the barrel. 60
5. A pneumatic weapon according to claim 4, wherein the barrel is carried in a bracket which is pivoted within, and confined against lateral movement by, an open-fronted clearance formed in the front of the air-chamber or body; the said clearance being in alignment with the barrel breech-seating at the rear of the said chamber or body. 65
6. Lock and safety mechanism, comprising a trigger having a tail engaging under the sear-tail, and a rotatable spring-influenced safety bolt adapted to be engaged with the tail of the trigger to prevent movement of the latter whilst leaving the sear free or unobstructed, said bolt being slideable transversely to the body of the weapon and provided externally with two recesses one or other of which engages a fixed retaining piece on the said body when the bolt is in either its "on" or "off" position. 70
7. A pneumatic weapon according to claim 1, wherein the barrel-actuated cocking mechanism is adapted to displace the piston within the air-chamber for cocking purposes, and provision is made for conveying air from the head of the said chamber to the bore of the barrel during the air-displacing stroke of the piston. 75

In testimony whereof they hereunto affix their signatures.
DOUGLAS VAUGHAN JOHNSTONE.
JOHN WILLIAM FEARN.
